United States Patent Office.

EDMUND SCHWIEDTER, OF HOBOKEN, NEW JERSEY.

Letters Patent No. 95,273, dated September 28, 1869.

COAL-STOVE.

The Schedule referred to in these Letters Patent and making part of the same.

To all whom it may concern:

Be it known that I, EDMUND SCHWIEDTER, of Hoboken, in the county of Hudson, and State of New Jersey, have invented a new and improved Heater; and I do hereby declare that the following is a full, clear, and exact description thereof, which will enable others skilled in the art to make and use the same, reference being had to the accompanying drawings, forming part of this specification.

Figure 1 represents a vertical transverse section of my improved heater.

Figure 2 is a vertical longitudinal section of the same.

Similar letters of reference indicate corresponding parts.

The object of this invention is to construct a heating-apparatus in which the smoke will be, to a very large degree, consumed, so that with a comparatively small quantity of fuel, a greater degree of heat can be obtained.

The invention consists in arranging, in front of the heater or on one or more sides above the grate, a vertical grate, which retains the fuel in place, and admits a side draught, that will enter below the upper burning-surface of the fuel. Such draught will cause the fuel that is ignited on top, to burn gradually downward, and the gas escaping from the burning fuel to be consumed by the glowing fuel above.

A, in the drawing, represents the body of the heater. The same is made of suitable material and of suitable form and size.

B is the fire-place;

C, the ordinary grate;

D, the ash-pit; and

a, the door leading to the ash-pit.

b is an opening through the front or side of the heater; it can be closed by a door, c, which is provided with a register, d.

On the inner side this opening is protected by a removable vertical grate, E.

Above the fire-place, and higher than the opening b,

is another opening, e, through the front or side of the heater, which can be closed by a door, f.

F is a pipe, through which the products of combustion can escape.

The operation is as follows:

The fuel is put through the upper door f until it is about in line with the upper end of the grate E, or even with the lower end of the aperture e.

Upon the ordinary fuel is then placed some igniting-matter, which will readily burn. When the same is well burning, the door f is closed, while the doors a and c are left open.

As soon as the upper portion of the ordinary fuel is also on fire, which can be observed through a small orifice in the door f, the doors a and c are also closed, and their registers d and g are slightly opened, to admit but little air. By means of these registers the fire can be regulated.

As the fire is gradually burning downward, the gases ascending from the burning portions, will pass through the upper glowing portions, and will, by the same, be consumed to a great extent.

Finally, the non-consumed portions escape through the chimney F.

The grate E serves to sustain the fuel, to admit air to and facilitate the stirring the same.

Having thus described my invention,

I claim as new, and desire to secure by Letters Patent—

1. The vertical grate E, arranged in a heater above the main grate C, substantially as herein shown and described, and for the purpose set forth.

2. The heater, provided with the apertures a, b, and e, and containing the grates C and E and the doors a, c, and f, all arranged substantially as herein shown and described.

The above specification of my invention signed by me, this 16th day of August, 1869.

Witnesses: EDMUND SCHWIEDTER.

FRANK BLOCKLEY,

GEO. W. MABEE.
